UNITED STATES PATENT OFFICE.

GEORGE DURHAM AND CHARLES W. MCGUIRK, OF SCRANTON, PENNSYLVANIA.

APPARATUS FOR CLEANING SURFACES.

1,135,001.

Specification of Letters Patent.

Patented Apr. 13, 1915.

Original application filed October 13, 1913, Serial No. 794,811. Divided and this application filed October 22, 1914. Serial No. 867,985.

To all whom it may concern:

Be it known that we, GEORGE DURHAM and CHARLES W. MCGUIRK, citizens of the United States, residing at Scranton, county 5 of Lackawanna, and State of Pennsylvania, have invented certain new and useful Improvements in Apparatus for Cleaning Surfaces, of which the following is a specification.

10 Our invention relates to apparatus for cleaning surfaces, especially those of locomotives and other vehicles by rapidly removing therefrom the accumulation of dust, mud, oily particles and the like with which 15 the frames, running gear, and other parts of such vehicles have become covered in use, the present application being a division of our application Serial No. 794,811, filed October 13, 1913.

20 As is well known, the accumulation of foreign matter upon the exterior of locomotives and other vehicles is frequently so great as to prevent careful inspection of the various parts, making it difficult and sometimes impossible to detect fractures or other imperfections, which, if not remedied, may cause 25 serious accidents. It is desirable, therefore, that the running gear and other parts of locomotives and other vehicles be frequently 30 cleaned, and it is customary to clean them by wiping off the foreign matters. This results, however, in an imperfect cleaning owing to the difficulty in getting at the complicated parts of the running gear and in getting the 35 accumulation of material out of the many recesses therein. To wash off these accumulations with streams of water has proven to be impracticable owing to the presence of oils and grease with which the accumulations 40 are commonly impregnated.

The object of our invention, therefore, is to provide an apparatus by means of which the accumulations on the locomotives or other vehicles may be rapidly removed and the frame and parts be left clean and free 45 from oil and other foreign matters.

We have discovered that if to a stream of water and oil, preferably mineral oil, the water in the stream being greatly in excess 50 of the oil, a stream of air at high velocity be admitted so as to break up the oil in the water into extremely minute particles and the stream be caused to impinge against the surfaces to be cleaned at the high velocity 55 imparted to the stream by the air, a most

effective and altogether unusual action takes place. For example, we have found in practice that if to a stream containing a mixture of oil and water in the proportion of about five hundred gallons of water to two gallons 60 of oil a stream of air at high velocity be admitted, preferably at or near the point of ejection of the stream that the impinging of this stream against the oily surfaces of locomotives, engines, or other vehicles entirely removes the oil and accumulated material from the surfaces, leaving them clean 65 and free from these matters.

In the accompanying drawings, Figure 1 is an elevation partly in section of our apparatus. Fig. 2 is a detail partly in section showing our preferred form of nozzle.

Referring to the drawings, 1 indicates a water supply pipe connected to any suitable source of supply of water under pressure, as 75 for example, the city water main. This supply may be regulated by a valve 2 of suitable construction. A T 3 attached to the water supply pipe 1 provides a connection for two branches of this supply pipe, the main branch 4 being provided at its discharge end with a nozzle 5, later more specifically described. The branch 4^a of the water supply pipe leads to the lower end 80 of a suitable tank 6, which may be of 85 suitable size for containing a quantity of oil. The branch 4^a may be controlled by a suitable valve 2^a. At its upper end this receptacle is connected to the water supply pipe 4, by a pipe 7, an indicator or 90 sight gage 7^a and a liquid controlling valve 7^b. The tank is provided with an inlet 8 having a removable cap or plug 8^a and also with a gage 9 provided with a drain 9^a for indicating the level of liquid in 95 the tank.

In the operation of the apparatus as thus far described, the storage tank is charged with oil, the valves 2 and 2^a are then opened, and water from the supply pipe 1 passes through the branches 4 and 4^a. The pressure of the water supply on the oil in the tank, the specific gravity of which should—in the form of apparatus shown—be less than that of the water, is thereby equalized, and the oil rises above the water in the tank and passes through the sight gage 7^a and pipe 7 into the branch 4 of the water supply pipe, through which the oil and water is conveyed to the nozzle 5. The proportion of oil 100 105 110

to be admitted to the water is regulated by the valve 7^b.

As hereinbefore described, we have discovered that by admitting to the stream of oil and water passing through the pipe 4 a stream of air under high velocity, the oil—contained in comparatively minute quantities in the stream of water—may be broken up into extremely fine particles. The stream 10 now consisting of water carrying in suspension the extremely fine particles of oil and air may be caused to impinge against the surfaces to be cleaned. We have discovered that the most effective cleaning takes place 15 if the air is admitted to the stream of oil and water at or near the point of ejection. We believe that the air should be admitted at a point sufficiently near the point of ejection that the oily particles so formed 20 by the admission of the air may be thrown against the surfaces to be cleaned while in their state of greatest activity as herein-after described. We prefer to use the form of nozzle shown in detail in Fig. 2, in which 25 the pipe line 4 connects to one end of the chamber 5^a of the nozzle, into which chamber the oil and water mixture from the pipe line 4 is received. This chamber 5^a has on one side a lateral extension 5^b into which 30 the air supply pipe 10 leads, this extension 5^b being formed between the end of the pipe 10 and the outlet of the chamber 5^a, which outlet is formed into a discharge orifice 5^c. As a possible explanation of these 35 phenomena, although we do not wish to be bound by this theory, it is our belief that by thus admitting the air to the mixture of oil and water at high velocity, the oil contained or carried in the water is so finely 40 sub-divided as to take the colloidal condition and owing to the excess of water and to the velocity of the stream the oil remains as a colloidal suspension. As is known, matter in this colloidal condition possesses great 45 energy of molecular attraction and particularly possesses the power when brought into contact with particles of foreign matter of uniting with the particles of foreign matter as a nucleus forming new combinations 50 therewith. The colloids of hydro carbons possess this molecular attraction to a high degree and also in this state have a tendency to condense or coagulate. In order, however, to insure this condensation or coagulation 55 there must be a nucleus of foreign matter or an electrical ion as the center of condensation or coagulation. When, therefore, the stream carrying oil in colloidal suspension is carried against the surface to be

cleaned with sufficient velocity to prevent 60 the colloids from uniting with each other, the colloids unite with the foreign matters upon the surface and form new combinations therewith so that the foreign matters are rapidly removed from the surface. 65

It is obvious that changes and modifications may be made in the form of apparatus which we have shown and described within the scope of our invention as set forth in the claims. 70

Having thus described our invention, what we claim is:

1. In an apparatus of the class described, the combination of a storage tank for containing a cleansing liquid, a water supply pipe connected with said tank, means for admitting liquid from the storage tank to the water supply pipe, a nozzle receiving said water and liquid from the water supply pipe, said nozzle being provided with an air receiving extension on one side thereof, and means for delivering air under pressure to said air receiving extension. 75

2. In an apparatus of the class described, the combination of a nozzle, a liquid supply pipe connected to the nozzle, means for admitting to the liquid supply pipe oil in an excess of water, and means at or near the nozzle for breaking up the oil into extremely minute particles and for impinging these 90 particles carried in the water against the surface to be cleaned. 85

3. In an apparatus of the class described, the combination of a water supply pipe, means for feeding a cleansing liquid in pre-determined quantities to the water in said pipe, and means remote from said liquid feeding means for breaking up the cleansing liquid into extremely minute particles while 95 said liquid is being carried in the water. 100

4. An apparatus of the class described, comprising, in combination, a nozzle provided with an enlarged chamber and a lateral extension having a discharge orifice, means for admitting to said chamber water 105 containing oil with the water in excess of the oil, and means for admitting to said lateral extension air under sufficient pressure to break up the oil into extremely minute particles at or near the point of 110 ejection of the oil and water from the nozzle and to impinge these particles against the surface to be cleaned. 115
